UNITED STATES PATENT OFFICE.

ROBERT B. EDWARDS, OF WORCESTER, MASSACHUSETTS.

SCYTHE-SNATH FASTENER.

SPECIFICATION forming part of Letters Patent No. 711,558, dated October 21, 1902.

Application filed January 3, 1901. Serial No. 41,964. (No model.)

To all whom it may concern:

Be it known that I, ROBERT B. EDWARDS, a citizen of the United States, residing at Worcester, in the county of Worcester and 5 Commonwealth of Massachusetts, have invented a new and useful Improvement in Scythe-Snath Fasteners, of which the following is a specification, accompanied by drawings forming a part of the same, in which—
10 Figure 1 represents the slabbed end of a scythe-snath to which the scythe is attached. Fig. 2 is a central longitudinal sectional view through the end of the scythe-snath on line 22, Fig. 1. Figs. 3, 4, and 5 represent, respectively, the pivoted plate, clamping-bolt, and flanged washer of my improved scythe-snath fastener detached from the scythe; and Fig. 6 is a transverse sectional view on line 66, Fig. 1.

20 Similar reference-letters refer to similar parts in the different views.

My invention relates to that portion of a scythe-snath fastener by which the shank of the scythe is adjusted on the snath so as to 25 vary the position of the scythe; and it consists in the construction and arrangement of parts hereinafter described, and set forth in the annexed claim.

Referring to the drawings, A denotes the 30 end of a scythe-snath slabbed at one side, as at B, and provided on its end with a ferrule C and having an eyebolt D; these parts being of the usual form of construction in snaths now in common use. Resting upon the 35 slabbed surface B is a plate E, provided at one end with a spur F, projecting from its under side and held in a hole F' in the scythe-snath, forming a pivot for the plate. The plate is provided with one or more openings 40 G to receive the usual lug on the shank of the scythe and an elongated opening H, concentric with the spur F, to receive a clamping-bolt I, having a head I' and carrying a nut I² and washer I³. Projecting from the under 45 side of the head I' and on diametrically opposite sides of the bolt are teeth J J, preferably triangular in their cross-section and adapted to engage a series of radial teeth K on the upper side of the pivoted plate E and 50 on its surface which is adjacent to the elon-

gated bolt-opening H. Recessed in the snath is a sleeve L, having a flange L', with its upper surface flush with the slabbed side B of the snath. The sleeve L fits tightly within the snath and surrounds the clamping-bolt I, 55 and its flange L' forms a bearing-surface for the under side of the pivoted plate E. The plate E, as shown in the drawings, is provided with two openings G G for the scythe-lug, a certain adjustment of the scythe being 60 obtained by moving the lug from one opening to the other. Another and finer adjustment of the scythe is secured by releasing the clamping-bolt I and swinging the pivoted plate E to bring a new tooth on the plate into 65 engagement with the teeth J on the bolt-head.

I am aware that it is not new to adjust the scythe by means of a pivoted plate held in any position by a clamping-bolt, and I do not claim such broadly. 70

What I claim as my invention, and desire to secure by Letters Patent, is—

In a scythe-fastener, the combination with a scythe-snath having a slabbed side and an eyebolt for receiving the shank of the scythe 75 of a socket-plate provided with an opening midway between its ends for the lug of the scythe-shank, said plate having at its end nearest said eyebolt a cylindrical projection on its under side entering a socket in the 80 snath and forming a pivot for said socket-plate, an elongated opening curved concentrically with said pivot in the end of said socket-plate farthest from said eyebolt for an adjusting-bolt, radial teeth on the upper 85 surface of said socket-plate and adjacent to said curved opening, an adjusting-bolt having teeth beneath its head to engage said radial teeth and a flanged sleeve recessed in the snath inclosing said adjusting-bolt and 90 having its flange flush with the slabbed side of the snath and bearing against the under side of said socket-plate, substantially as described.

Dated this 31st day of December, 1900.

ROBERT B. EDWARDS.
